Primary Examiner — Darlington Ly(74) *Attorney, Agent, or Firm* — Banner & Witcoff, Ltd.(57) **CLAIM**

The ornamental design for a nailer, as shown and described.

DESCRIPTION

FIG. 1 is a front perspective view of the nailer body showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The even broken lines in the drawings illustrate portions of the nailer that form no part of the claimed design.
